H. E. FREDERICK.
RAIL FASTENER,
APPLICATION FILED MAR. 25, 1916.

1,186,389.

Patented June 6, 1916.

UNITED STATES PATENT OFFICE.

HENRY E. FREDERICK, OF MONEY, MISSISSIPPI.

RAIL-FASTENER.

1,186,389.

Specification of Letters Patent. Patented June 6, 1916.

Application filed March 25, 1916. Serial No. 86,735.

To all whom it may concern:

Be it known that I, HENRY E. FREDERICK, a citizen of the United States, residing at Money, in the county of Leflore and State 5 of Mississippi, have invented certain new and useful Improvements in Rail-Fasteners; and I do hereby declare the following to be a full, clear, and exact description of the invention, such as will enable others skilled 10 in the art to which it appertains to make and use the same.

The object of this invention is to provide a novel type of rail fastener that will have a maximum securing efficiency and prevent 15 the spreading of the rails and of such simple construction that the same can be manufactured cheaply, will be durable, and will admit of the rail being secured in place expeditiously.

20 Other objects will appear and be better understood from that embodiment of my invention of which the following is a specification, reference being had to the accompanying drawing forming a part thereof, 25 in which:

Figure 1 is a side view of a tie, showing the rail thereon in cross section and the manner of securing the rail to the tie with the improved rail fastener, Fig. 2 is a top plan 30 view of a base plate of the fastener removed from operative position, and Fig. 3 is a fragmentary plan view of a modified form of base plate.

Referring to the drawing more in detail, 35 the letter A designates a tie and B a rail.

The fastening device comprises a base plate 1, which engages under the base flange of the rail B and rests on the upper side of the tie A, and has its opposite ends extending 40 beyond the longitudinal edges of the base flange, as shown in Fig. 1 of the drawing. A transversely extending rail base-engaging flange 2 is formed on the inner end of the base plate 1, at a point spaced from the terminal 45 of the inner end of the base plate, and engages over the inner side of the base flange of the rail B, and the said inner end of the base plate 1 is provided, adjacent the inner terminal, with an opening 3 for the 50 reception of a suitable spike, not shown, and which is adapted to be driven into the tie and serve to hold the base plate in position. The opposite or outer end of the base plate is provided, at a point spaced inwardly of 55 the outer terminal, with another spike-receiving opening 4 for the reception of a

spike, designated 5, the flanged head of which is adapted to engage over the adjacent side of the base flange of the rail, as shown in Fig. 1 of the drawing. The outer end of the base plate is also provided, on opposite sides of the opening 4, with elongated slots 6, the inner ends of which extend beyond the inner side of the opening 4. Spaced blocks 7 are formed integrally with 60 the upper side of the outer end of the base plate 1, and are located on opposite sides of the opening 4 and have their inner sides lying flush with the outer walls of the slots 65.

In securing the rail in place, the rail is 70 positioned on the base plate and wedge-shaped members, designated 8, are inserted into the slots 6 and driven into the tie A, the said wedge-shaped members 8 having their inner sides engaging the adjacent longitudinal edge of the base flange of the rail, so that during the downward movement of the wedge-shaped members the rail will be moved laterally and engage the inner side of the base flange beneath the rail-engaging flange 2. The spike 5 is then driven through 75 the opening 4 and has the flanged head thereon engaged over the outer side of the base flange of the rail.

In the structure shown in Fig. 3 the inner end of the base plate 1 is of a length greater than the length of the inner end of the base plate shown in Figs. 1 and 2 of the drawing, and is provided with an additional spike-receiving opening, designated 9. 80 This construction of plate is designed particularly to secure the rails at curves.

Having thus described my invention what I claim as new is:

1. A rail fastener comprising a base plate 95 adapted to engage beneath the base flange of a rail and having its opposite ends extending beyond the sides of the base flange, means located on the inner end of the base plate for engaging the adjacent side of the base flange of the rail, the outer end of the base plate being provided with an opening and a pair of slots located on opposite sides of the opening, base flange-engaging means extending through the opening, and wedge-shaped members extending through the slots in the adjacent base flange. 100

2. A rail fastener comprising a base plate adapted to engage beneath the base flange of a rail and having its opposite ends extending beyond the sides of the base flange, means on the inner end of the base plate for 110

- engaging the inner side of the base flange of the rail, the outer end of the base plate having a plurality of slots therein, blocks located at the outer end of the base plate and 5 having their inner sides lying flush with the outer end walls of the slots, and base flange-engaging members extending through the slots and engaging the inner sides of the blocks.
- 10 3. In combination with a rail tie and a rail thereon, of a base plate mounted on the tie and beneath the rail and having its opposite ends extending beyond the opposite sides of the base flange of the rail, base 15 flange-engaging means located on the inner

end of the base plate, the outer end of the base plate having an opening therein and having elongated slots located on opposite sides of the opening, each of the slots having one end extending beyond the inner wall 20 of the opening, and base flange-engaging members extending through the opening and the slots and engaging in the tie.

In testimony whereof I affix my signature in presence of two witnesses.

HENRY E. FREDERICK.
